Charles S. Gage, Cold Spring on Hudson, N. Y.,
assignor to Lenthalic Incorporated, New York,
N. Y., a corporation of New York

Application October 19, 1934, Serial No. 53,682

Term of patent 3½ years

To all whom it may concern:

Be it known that I, Charles S. Gage, a citizen of the United States, residing at Cold Spring on Hudson, in the county of Westchester and State of New York, have invented a new, original, and ornamental Design for a Combined Display Stand and Container for Toilet Accessories, of which the following is a specification, reference being had to the accompanying drawing, forming part thereof:

In the drawing, the figure is a perspective view of a combined display stand and container for toilet accessories showing my new design.

I claim:

The ornamental design for a combined display stand and container for toilet accessories, substantially as shown.

In witness whereof I affix my signature.

CHARLES S. GAGE.
